UNITED STATES PATENT OFFICE.

JOHN TOUCH AND DOMINIC F. TOUCH, OF ARCHBALD, PENNSYLVANIA.

AUTOMATIC STOP MECHANISM.

Application filed October 18, 1921. Serial No. 508,585.

To all whom it may concern:

Be it known that we, JOHN TOUCH and DOMINIC F. TOUCH, citizens of the United States, residing at Archbald, in the county 5 of Lackawanna and State of Pennsylvania, have invented certain new and useful Improvements in Automatic Stop Mechanism, of which the following is a specification.

This invention relates to automatic stop 10 mechanism and more particularly to a mechanism designed to stop the operation of an electric motor in the event of slipping or breakage of a belt or chain driven by said motor, or a breakage of any piece of machinery indirectly driven by the motor.

Generally speaking the object of the present invention is to provide in connection with a line shaft or similar driven part, and an electric motor for driving said part, 20 means for automatically breaking the motor circuit in the event the speed of rotation of the shaft is decreased beyond a predetermined limit.

The figure of the accompanying drawing 25 represents a view partly in elevation and partly diagrammatic illustrating the mechanism embodying the invention.

In the drawing the numeral 1 indicates an electric motor of any type and the numeral 30 2 indicates a line shaft which is driven, as for example by a belt 3 and pulleys 4 from the shaft of the motor 1. The shaft 2 is designed to transmit power to any desired number of machines, and the present invention 35 has as its object the provision of means for breaking the circuit to the motor 1 in the event of breakage or slipping of the belt 3 or stopping of any of the machines, driven from the line shaft 2, through any accidental cause. The motor circuit is indicated 40 in general by the numeral 5 and embraces a knife switch 6 provided with the usual handle 7 whereby it may be conveniently thrown. This switch is preferably mounted 45 upon a base block which is indicated by the numeral 8 and there is also mounted upon this block an electric motor indicated by the numeral 9 which motor may be of small size and is provided with the usual shaft 10. A 50 cam 11 is fixed upon the shaft and, in the rotation of the shaft, is designed to ride against one end of a rock lever which is indicated by the numeral 12 and which is pivotally supported as at 13 upon the base block 8. The other end of the lever 12 projects 55 beneath the handle 7 of the knife switch 6

and when the parts are at rest and in normal positions the cam 11 will be out of engagement with the said rock lever 12 and the lever will be tilted to about the position 60 shown in the drawing, the switch 6 being closed and the handle 7 of the switch resting in engagement with the last mentioned end of the said rock lever. However, it will be evident that when the motor 9 is energized, 65 the rotation of the shaft 10 of the motor will result in the cam 11 being brought into engagement with the end of the rock lever 12 thus rocking this lever upon its fulcrum and elevating its end which is engaged beneath the switch handle 7. This movement 70 of the rock lever will serve to throw the switch to open position and it will remain in this position until again manually closed, at which time, of course, the rock lever 12 75 will be restored to normal position illustrated in the drawing.

The circuit in which the electric motor 9 is located embraces conductor wires 14 and 15, and the wire 15 leads to one terminal of 80 a battery or other source of electric current supply indicated by the numeral 16. The wire 14 leads to a fixed contact member 17 which is mounted upon some suitable fixed support located in proximity to the shaft 2. 85 A wire 18 leads from the other terminal of the battery 16 to a bracket 19 which is also fixed in proximity to the shaft 2 and suitably spaced from the contact 17. The numeral 20 indicates in general a governor 90 which is associated with the shaft 2 and this governor comprises a head 21 which is fixed with relation to the bracket 19 and in electrical circuit therewith, and a head 22 which is slidable upon the shaft 2, these 95 heads being connected by the usual spring arms 23 carrying the centrifugal balls 24. When the shaft 2 is at rest the head 22 of the governor 20 will be in electrical contact with the contact member 17 and the circuit 100 will be closed through the motor 9. When the shaft is rotating, however, at a proper rate of speed, the centrifugal action of the balls 24 of the governor will draw the head 22 out of engagement with the contact 17 105 and no current will flow through the motor 9. Under these conditions, which are normal, the switch 6 will remain closed to close the circuit through the motor 1, but should the belt 3 slip or break or should the speed 110 of rotation of the shaft 2 for any other reason be retarded below a predetermined

limit, the head 22 of the governor 20 will come into engagement with the contact member 17 thus immediately closing the circuit through the motor 9 and effecting a 5 rocking movement of the lever 12 to throw the switch 6 to open position thus breaking the circuit through the motor 1.

It may at times be desirable to close the 10 circuit through the motor 9 from a distant point and with this object in view an electric push button switch or a switch of any other suitable type indicated by the numeral 25 is placed in a shunt circuit 26 with the motor circuit.

15 It is also preferable that a bell or other signal 27 be placed in a shunt circuit 28 with the motor circuit so as to give warning at the time the circuit is closed through the motor 9.

20 Having thus described the invention, what is claimed as new is:

1. In mechanism of the class described, the combination with a motor circuit, a motor in said circuit, a switch in said circuit, and 25 an element driven from the motor, of means operable automatically to throw the switch to break the motor circuit upon variation in speed of the said driven element beyond a predetermined rate, the said means comprising a rock lever arranged when rocked 30 in one direction to throw the switch to break the motor circuit, an electric motor, means operated through said second-mentioned motor for coaction with the rock lever to so move the same, a circuit in which the last 35 mentioned motor is located, a fixed contact element in the second mentioned circuit, and a contact element also in said second mentioned circuit adapted to be moved with 40 relation to the first mentioned contact element in accordance with variation in speed of the said driven element.

2. In mechanism of the class described, the combination with a motor circuit, a 45 motor in said circuit, a switch in said circuit, and an element driven from the motor, of means operable automatically to throw

the switch to break the motor circuit upon variation in speed of the said driven element beyond a predetermined rate, the said 50 means comprising a rock lever arranged when rocked in one direction to throw the switch to break the motor circuit, an electric motor, means operated through said second-mentioned motor for coaction with the rock lever to so move the same, a circuit in which the last mentioned motor is located, a fixed contact element in the second mentioned circuit, a contact element also in said second mentioned circuit adapted to be moved with relation to the first mentioned contact element in accordance with variation in speed of the said driven element.

3. In mechanism of the class described, the combination with a motor circuit, a motor in said circuit, a switch in said circuit, and an element driven from the motor, of means operable automatically to throw the switch to break the motor circuit upon variation in speed of the said driven element beyond a predetermined rate, the said 70 means comprising a rock lever arranged when rocked in one direction to throw the switch to break the motor circuit, an electric motor including a shaft, a cam upon the shaft rotatable therewith and positioned for coaction with the said rock lever to rock 75 the same when the second mentioned motor is energized, a circuit in which the last-mentioned motor is located, a fixed contact element in the second mentioned circuit, and a contact element also in said second mentioned circuit adapted to be moved with relation to the first-mentioned contact element in accordance with variation in speed of the 80 said driven element.

In testimony whereof we affix our signatures.

JOHN TOUCH.
DOMINIC F. TOUCH.
